UNITED STATES PATENT OFFICE.

DANA E. HARDING, OF ARLINGTON, MASSACHUSETTS, ASSIGNOR TO HARDING ENGINEERING COMPANY, OF EAST BOSTON, MASSACHUSETTS, A CORPORATION OF MASSACHUSETTS.

VERTICAL ROTARY GLAZING MACHINE.

Application filed August 8, 1925. Serial No. 48,947.

My present invention relates to the manufacture of leather from skins and hides, and more particularly to an improved machine for performing the operation known as glazing.

In performing the operation of glazing on leather as one of the finishing processes thereof, it has been the universal practice to employ a machine known as a glazing jack and which machine carries a cylindrical block of glass, agate, porcelain or the like held in an arm which is reciprocated by power. The reciprocatory motion of the arm has been considered necessary in order to obtain a structure in which the desired pressure may be imparted to the glazing roll as it is drawn over the leather, the structure of the machine being such that the glazing roll is given a four sided or rectangular motion. The glazing arm reciprocates at high speed and it has been impossible to devise a machine of this character in which excessive vibration will not be set up, both to the machine and to the building in which the same is located. Buildings in which the batteries of glazing machines are located must be periodically shored up and strengthened in order to withstand the vibrations caused by these machines. In addition, such machines are exceedingly dangerous as the head carrying the glazing roll is relatively heavy and being shot forward with great rapidity, causes serious damage to a workman or other person who accidentally comes within their reach. As the workman must sit in proximity to the anvil on which the leather is being held, and therefore in proximity to the reciprocating glazing head, the danger of accidents is always imminent and a number of painful and serious accidents occur in every glazing plant throughout the country. Various attempts have been made to cover or shield the glazing head so as to prevent a workman accidentally coming within range thereof, but, due to the nature of the operation, these attempts have not been successful. No progress so far as I am aware has been made in successfully eliminating the vibration of these machines nor the effects of such vibrations on buildings.

In my present invention I have obviated the defects in prior constructions and have devised a glazing jack or machine in which

a rotary motion is imparted to the glazing roll, thereby eliminating the vibration and, further, have produced a device with which a safety shield may be associated to thereby eliminate accidents and, further, have devised a machine in which the leather being operated on need no longer be held by the operator as this feature in prior machines was a prolific source of accidents.

In carrying out my invention I have provided an arcuate anvil over which successively move glazing rolls equally spaced about the periphery of a wheel or disc mounted for rotation on a horizontal axis. Associated with the anvil and controlled by the rotating axis of the disc is a leather gripping device which operates automatically to intermittently hold and release the leather being worked upon.

The principal object of my invention, therefore, is an improved glazing machine.

Another object of my invention is an improved glazing machine of the rotary type.

A further object of my invention is an improved leather holding device for glazing machines.

Other objects and novel features of the construction and arrangement of parts comprising my invention will appear as the description of the invention progresses.

In the accompanying drawings illustrating the preferred embodiment of my invention,

Fig. 1 is a side elevation;

Fig. 2 is a rear elevation, and

Fig. 3 is a sectional elevation on the line 3-3 of Fig. 1.

Referring to the drawings, 10 designates a base at one end of which is secured a pair of pedestal members 11, such members being spaced apart from each other and extending upwardly and forwardly to any suitable height or point. Formed on the top ends of the pedestal members 11 and in alignment with each other are bearings 12 in which is rotatably mounted a shaft 13. This shaft 13 extends laterally outward from one of the pedestals 11 and is provided on such laterally extending end with tight and loose pulleys 14 and 15 respectively, a collar 16 secured to the end of the shaft 13 preventing longitudinal movement of such pulleys 14 and 15 on the shaft. Between the ped-

estals 11 and secured to the shaft 13 is a wheel or disc 17, this wheel or disc consisting primarily of a hub portion 18 having formed integral therewith and extending radially outward therefrom the equally spaced arms 19. At the extremity of each of the arms is provided a split holding device 20 and in each of the split holding devices is secured, in any suitable manner, a cylindrical glazing block 21 of glass, agate, or any other suitable material. The extremities of the arms 19 are connected together by members 22 constituting, in reality, the periphery or rim of the wheel or disc 17. Secured to the shaft 13 adjacent to the pedestal 11 remote from the tight and loose pulleys 14 and 15 respectively is a disc 24 provided with a plurality of cam faces 25 on the periphery thereof. These cam faces are equal in number to the number of glazing blocks 21 on the rotatable member 17 and the position of the cam faces 25 and blocks 21 bear a certain relation to each other that will be pointed out hereinafter.

Secured to the base 10 and spaced apart from each other are pedestals 26 and 27. The pedestal 26 is greater in height than the pedestal 27, and connecting the two pedestals from a point adjacent to their top ends is an arcuate plate or member 28. The upper surface of the arcuate member 28 is on a radius that has the drive shaft 13 as a center. The member 28 is substantially T-shaped in cross section, as may be seen from an inspection of Fig. 3, and threaded through the top portion of the T at intervals along each edge thereof are thumb screws 29. Mounted on the top surface of the member 28 and resting on the upper ends of the thumb screws 29 is an anvil comprised of an arcuate shaped steel plate 30 on which is secured an arcuate rubber buffer 31, and secured to the upper surface of the buffer 31 is an arcuate anvil face 32, preferably of cast iron, although any other suitable material may be employed. Cemented to the upper and arcuate surface of the anvil 32 is a leather facing 33 and on which may rest the sheet of leather 34, the grain side of which is to be glazed. The ends of the pedestals 26 and 27 which extend upward beyond the arcuate member 28 form abutments which limit any possible movement of the anvil on the arcuate member 28. Secured to the sides of the pedestal 26 and also secured to the sides of the pedestals 11 and extending upwardly therefrom are braces 35 and 36 respectively, such braces having their upper ends terminating adjacent to the upper surface of the anvil 32. Secured to the upper ends of these braces 35 and 36 on each side of the apparatus are table members 37 which, as may be seen from an inspection of Fig. 3, form a support on which the sheet of leather 34 is maintained horizontal.

On the forward face of the pedestal 26 is a member 38 and in this member is pivotally mounted, intermediate its ends, a clamping lever 39. The upper portion of this clamping lever terminates in a curved end 40 that engages with the rounded face of the upper end of the pedestal 26. Between the pivot point 38 and the rounded end 40 and lying between the lever 39 and the pedestal 26 is a coil spring 41 which tends to force the curved end 40 out of engagement with the rounded upper end of the pedestal 26. Pivotally attached to the lower end of the lever 39 and extending rearwardly above and substantially parallel to the base 10 is a connecting rod 42. This connecting rod is pivotally attached to the end of one arm of a bell crank lever 43 that is rotatably mounted on a shaft 44 secured to one of the pedestals 11. The end of the other arm of the bell crank lever 43 is pivotally attached to the lower end of an operating rod 45, this rod extending upwardly through a guide-way 46 secured to one of the pedestals 11 and is provided at its upper end with a rotatably mounted roller 47 adapted to engage with the cam faces 25 on the cam disc 24. Also attached to the end of the other arm of the bell crank lever 43 is one end of a coil spring 48, the other end of this coil spring being attached to a pin 49 secured to one of the pedestals 11.

The spring 48 tends to force the operating rod 45 upwardly and to maintain the same in engagement with the cam faces 25 and the cam disc 24 and, also, through the bell crank lever 43 and connecting rod 45, rotates the lever 39 about its pivot point and moving the rounded end 40 of such lever 39 away from the front face of the pedestal 26. When the various cams 25 come into engagement with the roller 47, the operating rod 45 is moved downwardly and, through the connections above described, causes the rounded end 40 of the lever 39 to engage with the upper rounded end of the pedestal 26 and if, under these circumstances, a hide or skin 34 is in position on the apparatus, such hide or skin will be held firmly against movement. The relation of the cams 25 with respect to the glazing blocks 21 is such that a clamping action by the curved end 40 on the hide or skin 34 takes place during the time that the blocks 21 are in engagement with the leather facing 33 on the anvil, and when such blocks 21 are no longer in engagement with such leather facing 33, the cams 25 will have moved past the roller 47, allowing such roller by means of the spring 48 to move into engagement with the cam disc 29 and thus freeing the leather 34 from engagement by the curved end 40 of the lever 39. The time between the release of the lever 34 and the next consecutive gripping of such leather will be sufficient to allow the

operator of the apparatus to move the leather 34 to any position desired on the anvil and bring a new surface into position to be operated on by the glazing block 21.

5 By means of the thumb screws 29, the degree of pressure of the glazing blocks 21 on the leather 34 may be regulated. The member 17, being substantially circular, and the anvil on which the blocks are carried by such member 17 being also circular, the vibratory movement of prior devices is entirely eliminated. My present apparatus is capable of having the glazing blocks 21 move at a much higher surface speed than is possible in

10 a reciprocating apparatus. Further, the workman is relieved of all necessity of holding onto the leather 34 during the glazing operation and can thus keep working at top speed for a longer time than is possible with other machines and with much less fatigue.

15 Being less fatigued, he is more alert and the liability to accidents from a tired operator is eliminated.

While I have necessarily shown and described the preferred embodiment of my invention somewhat in detail, it is to be understood that I may vary the size, shape, and arrangement of parts comprising my improved apparatus within wide limits without departing from the spirit of the invention.

Having thus described my invention, what I claim as new is:

1. An improved glazing jack, comprising an anvil, means for holding a hide or skin thereon, a plurality of glazing blocks adapted to move over said anvil and in engagement with the hide successively, and

means associated with the glazing blocks for controlling the holding means.

2. An improved glazing jack, comprising an anvil, means for holding a hide or skin thereon, a plurality of glazing blocks adapted to move over said anvil and in engagement with the hide successively, and means associated with the glazing blocks for maintaining the holding means in engagement with the hide only during the time the glazing blocks are in engagement with the hide.

3. An improved glazing jack, comprising an anvil, means for holding a hide or skin thereon, a cylindrical member associated with said anvil, a plurality of glazing blocks mounted on the periphery of said cylindrical member and adapted to move over said anvil successively and in engagement with the hide, and means associated with the glazing blocks for controlling the holding means.

4. An improved glazing jack, comprising an anvil, means for holding a hide or skin thereon, a cylindrical member associated with said anvil, a plurality of glazing blocks mounted on the periphery of said cylindrical member and adapted to move over said anvil successively and in engagement with the hide, and means associated with the glazing blocks for maintaining the holding means in engagement with the hide only during the time the glazing blocks are in engagement with the hide.

In testimony whereof, I have signed my name to this specification.

DANA E. HARDING.
